UNITED STATES PATENT OFFICE

2,486,609

ROPE-SPINNING TOY

James R. O'Neil, San Francisco, Calif.

Application March 26, 1947, Serial No. 737,347

1 Claim. (Cl. 46—1)

1

This invention relates to improvements in spinning ropes and has particular reference to the spindle which will permit the operator to rotate or spin a relatively small loop with either hand, thus accomplishing a change from a low position to a high position, changing the hands during the spinning operation with a minimum of skill and practice.

A further object is to produce a device of this character which is economical to manufacture, one wherein the device provides a new and simple technique readily learned by the average person.

Other objects and advantages will be apparent during the course of the following description.

In the accompanying drawings forming a part of this specification and in which like numerals are employed to designate like parts throughout the same,

Fig. 1 is a perspective view of one form of swivel.

Fig. 2 is a view showing my swivel in use when the loop is in a low position and holding the swivel from the top.

Fig. 3 is a similar view showing a high position of the swivel and holding the same from the bottom.

The ordinary type of spinning rope is difficult to operate or manipulate, requiring considerable skill beyond that of the juvenile, and I have, therefore, devised a rope which is especially easy to manipulate. A swivel is provided having two handles, either one of which may be grasped, enabling the operator to use either hand at will, or to transfer from one to the other while the rope is in use.

Thus, the spinning of the rope to form a circular loop may be started as a low spin, i. e., the loop being brought to circular formation adjacent the waistline of the user, and then elevated and held at a point adjacent the head of the user.

It is, of course, understood that the hand which is manipulating the rope is kept moving in a rotary direction at all times in order to impart rotary movement to the rope.

In the accompanying drawings wherein for the purpose of illustration is shown a preferred embodiment of my invention, the numeral 5 designates a bar, the ends of which are enlarged as shown at 6 and 7.

This bar is provided with a pair of spaced discs 8 and 9 formed substantially midway of the end of the bar. This arrangement divides the bar into handle portions A and B.

2

Between the discs 8 and 9 I place a small loop or eye 11 of the rope 12, which rope has a relatively large loop 13 formed upon its free end by suitably knotting the rope. It is necessary to have two discs such as 8 and 9 so that the rope may be spun to bring the large loop into a vertical plane or any plane between horizontal and vertical without causing the eye to slide along the bar.

It is here understood that the bar 5 with its discs 8 and 9 is a preferred form, but that I may construct my swivel in any desired manner so that the same results are accomplished, i. e., a double ended handle with means for securing the loop of a rope substantially midway of its length.

With this arrangement, by grasping the handle A, as shown in Fig. 2, and imparting a rotary movement in a horizontal plane, the rope 12 will rotate about the rod through the action of the looped connection 11 between the discs, and this movement in turn will cause the rope 12 and the loop 13 to spin, the loop 13 assuming a horizontal position.

After the loop has once started to spin it may be maneuvered from the position of Fig. 2 to that of Fig. 3, the operator releasing the top portion A of the swivel and grasping the bottom portion B of the swivel.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having thus described my invention, I claim:

In a device of the kind described, the combination with a bar having a centrally disposed pair of spaced discs, said bar being provided with a handle at each end, and a rope having an eye at one end fitting revolubly on the bar between said discs, said rope having its other end doubled upon itself and secured to form a relatively large permanent loop.

45 **JAMES R. O'NEIL.**
